(57) **CLAIM**

The ornamental design for a display screen with a reservation graphical user interface, as shown and described.

DESCRIPTION

The figure is a front view of a display screen with reservation graphical user interface, showing our new design. The outermost broke lines in the figure illustrate a display screen, which is the environment of the design, and forms no part of the claim. The remaining broken lines, including all text and icons, illustrate portions of the graphical user interface that form no part of the claimed design.
